UNITED STATES PATENT OFFICE.

GEORGE L. ADAMS, OF FOWLERVILLE, MICHIGAN, ASSIGNOR OF ONE-HALF
TO JOHN C. ELLSWORTH, OF SAME PLACE.

PRINTING-PRESS.

SPECIFICATION forming part of Letters Patent No. 276,207, dated April 24, 1883.

Application filed April 26, 1882. (No model.)

To all whom it may concern:

Be it known that I, GEORGE L. ADAMS, of 5
Fowlerville, in the county of Livingston and
State of Michigan, have invented new and
useful Improvements in Printing-Presses; and
I hereby declare that the following is a full,
clear, and exact description thereof, reference
being had to the accompanying drawings,
which form a part of this specification.

10 The nature of this invention relates to cer-
tain new and useful improvements in the con-
struction of hand printing - presses, by means
of which the same are very much simplified
in construction, cheapened in cost, and ren-
dered very easy to operate.

15 The invention consists in the peculiar ar-
rangement of devices for readily and easily
controlling the position of the impression-cyl-
inder, and in the peculiar construction and
20 combination of parts, as more fully hereinaf-
ter described.

Figure 1 is a perspective of my improved
press. Fig. 2 is a detail, and Fig. 3 is a sec-
tional elevation thereof.

25 In the accompanying drawings, A A' repre-
sent a pair of ways or ribs supported parallel
to each other upon any suitable supports or
standards. The ribs A and A', upon their up-
30 per surfaces, are V-shaped in cross - section,
and it is preferable that both these ribs be
provided with parallel projecting flanges a, to
prevent the oil used in lubrication from es-
caping to the floor below. Across and under-
35 neath these ribs is suitably journaled the
shaft C, upon which, between said ribs, is se-
cured a pulley, B, to which are secured straps
b or other devices, the opposite ends of which
are secured to the bed D of the press, so that
40 in the rotation of the shaft in one direction the
bed is driven toward one end of the ribs, and
when the motion of said shaft is reversed a
reverse motion is given to the bed. The shaft
C is provided with a crank, E, for this purpose.

45 D represents the bed of the press, which is
made in the usual way and provided with the
usual means for attaching the tympan. In-
stead of running in slideways or slide-ribs, as
is usual in hand-presses, this bed travels upon
small wheels or friction-rollers, the peripher-

ies of which rollers have V-shaped grooves, to 50
engage with and travel upon the V-shaped
ribs A A', which act as guides. F are sup-
ports at the forward ends of the ribs, and
within the upper parts of these supports are
sliding boxes G, in which run the journals of 55
the impression-roller H. These boxes are ver-
tically adjustable by means of the set-screws
I above and below. Between the top of these
boxes and the standards which support them
are springs O, designed by their own tension 60
to force said roller downward, aiding its own
gravity in producing the necessary impression
upon the form upon the bed of the press as
said form passes under said roller. As the
bed of the press, containing the form, is pro- 65
jected underneath said roller, the roller should
occupy a position sufficiently above to allow
said form to pass without obstruction; but
the moment the reverse motion of the bed com-
mences the weight of the roller, assisted by 70
the springs above it, should be thrown upon
the form to obtain the desired impression. To
accomplish this end I pivot the lever J to one
side of the rib A', as represented in Fig. 3, or
to any other convenient place, by a bracket, as 75
shown in Figs. 1 and 2. To the under side of
this lever I hinge or otherwise suitably secure
the link L, the free end of which connects to
one end of a lever, K, pivoted to an arm be-
80 low the ribs A A', the opposite end of said
lever K being connected to a yoke, M, whose
ends are connected with the lower ends of the
boxes G, in which the impression-roller rotates.

In practice, as the pressman grasps with his
left hand the crank by which the bed is pro- 85
pelled, with his right hand he throws down
the tympan upon the form, and as this latter
movement is completed his hand drops off the
tympan onto the free end of the lever J, and,
bearing down upon the same with sufficient 90
force, raises the impression-roller through the
system of leverage described, and allows the
bed to pass freely in the forward direction un-
der the action of the shaft. Before or at the
time the return or reverse movement of the 95
bed takes place the operator should release
the lever, when the gravity of the roller, as-
sisted by the action of the springs above it,

will throw it down sufficiently far so that as such reverse motion takes place the proper impression will be had.

When it is desired to suddenly increase the pressure extended by the roller, the operator can at any time add to the downward action of the roller and springs by raising the lever instead of releasing it. The yoke M, being solid and provided with the arm M', placed as near its center as the mechanical exigencies of the case will permit, is rendered capable of exerting considerable force equally upon both the boxes and from them upon the roller, whether for raising or lowering the same.

15 What I claim as my invention is—
In a hand printing-press, the three-armed

yoke M and sliding boxes G, secured thereto, in combination with the pivoted lever K, secured to the downwardly-extending arm M' of said yoke, extending rearwardly under the 20 bed of the press, suitable pivoted hand-lever, J, arranged transversely to the bed, and connecting-link L, substantially as shown and described.

In witness that I claim the above-described 25 invention I have hereunto set my hand this 18th of March, 1882.

GEORGE L. ADAMS.

In presence of—

H. S. SPRAGUE,
E. SCULLY.
